UNITED STATES PATENT OFFICE.

INGENUIN HECHENBLEIKNER, OF CHARLOTTE, NORTH CAROLINA, ASSIGNOR TO
CHEMICAL CONSTRUCTION COMPANY, OF CHARLOTTE, NORTH CAROLINA, A
CORPORATION OF NORTH CAROLINA.

APPARATUS FOR SPRAYING LIQUIDS.

1,273,856.

Specification of Letters Patent. Patented July 30, 1918.

Application filed February 14, 1918. Serial No. 217,973.

To all whom it may concern:

Be it known that I, INGENUIN HECHENBLEIKNER, a citizen of the United States, residing at Charlotte, in the county of Mecklenburg and State of North Carolina, have invented certain new and useful Improvements in Apparatus for Spraying Liquids, of which the following is a specification.

My invention relates to apparatus for distributing or spraying liquids, such as acids, into the tower of a concentrating apparatus, while in no sense restricted to this particular use.

An important object of the invention is to provide an apparatus of the above mentioned character, so constructed that when the apertures thereof become clogged, and the acid or the like cannot discharge therefrom, the acid will then be discharged through a tubular member, in a manner to prevent the acid being wasted or improperly distributed.

A further object of the invention is to provide apparatus of the above mentioned character, having means whereby the operation thereof may be at all times readily observed by the attendant or the like.

A further object of the invention is to provide means to readily cleanse or flush the clogged apertures of the apparatus.

A further object of the invention is to provide apparatus of the above mentioned character, which is simple in construction, inexpensive to manufacture, strong and durable.

Other objects and advantages of the invention will be apparent during the course of the following description.

In the accompanying drawings forming a part of this specification and in which like numerals are employed to designate like parts throughout the same,

Figure 1 is a side elevation of apparatus embodying my invention, showing the same in use,

Fig. 2 is an enlarged central longitudinal sectional view through the apparatus, and,

Fig. 3 is a horizontal sectional view taken on line 3—3 of Fig. 2.

In the drawings, wherein for the purpose of illustration is shown a preferred embodiment of my invention, the numeral 5 designates the tower of an acid concentrating apparatus. This tower is preferably formed

of brick, which is adapted to withstand the action of the acid. The tower may be partly filled with aggregates 6, formed of acid resisting material.

The upper end of the tower 5 is covered by a head 7, having an opening for the reception of a sleeve 8, having an upper flange 9. This sleeve is formed of acid resisting material.

My improved distributor is designated as a whole by the numeral 10, and embodies a tubular body portion 11, inserted within the sleeve 8, as shown. This body portion 11 has a flange 12, which contacts with the top of the flange 9, thereby supporting the distributor. The tubular body portion 11 is provided at a point near and spaced from its upper end with an acid receiving chamber 13, preferably formed integral therewith. Arranged within the chamber 13 is an upwardly extending annular flange 14 forming in effect a continuation of the tubular body portion 11. The flange 14 forms with the wall of the chamber 13, an annular passage or pocket 15. The top of the chamber 13 is formed open and the acid may be fed therein by any suitable means. The floor or bottom 16 of the chamber 13, between the flange 14 and the side wall of the chamber, is provided with spaced spacing ribs or elements 17, for a purpose to be described.

The floor or bottom 16 projects inwardly beyond the flange 14 and is provided inwardly of the same with a central opening 18 and discharge openings 19, arranged about the central opening, as clearly shown in Fig. 3.

As more clearly shown in Fig. 2, the lower end of the tubular body portion 11 is tapered, as shown at 20, to provide a nozzle having apertures 21, suitably angularly arranged, as shown.

At its lower end, the tapered portion or nozzle 20 has a tapered opening 22, preferably decreasing in diameter downwardly. This tapered opening is adapted to function as a valve seat and is covered and uncovered by a tubular valve 23, formed upon or carried by the lower end of an inner over-flow tube or pipe 24. Particular attention is called to the fact that the lower end of the valve 23 is open and the upper end of the over-flow pipe 24 is also open. The upper end of the over-flow pipe 24 preferably pro-

jects above the floor 16 for a slight distance, whereby the over-flow pipe may be readily engaged, when it is desired to elevate the same.

5 The distributer preferably has all parts thereof made of acid resisting material, as is obvious.

The numeral 25 designates a cup-shaped cover, preferably formed of glass or other 10 transparent material, which is not acted upon by acids. This cover surrounds the upper end of the flange 12 and is supported in spaced relation from the floor 16 by the ribs 17. The cover 25 preferably carries a 15 knob 26, by means of which the cover may be conveniently raised.

The operation of the apparatus is as follows:

The acid to be concentrated is fed into the 20 chamber 13 by any suitable means, and passes beneath the lower edge of the cover 25. When a sufficient amount of acid is fed into the chamber 13 it over-flows about the upper end of the flange 14 and gravitates through 25 the openings 19 into the tubular body portion 11, exteriorly of the over-flow pipe 24. This acid then travels downwardly within and through the tubular body portion 11 and discharges therefrom through the apertures 30 21, and is thereby distributed in the proper manner in the tower 5. As is well known, the acid not infrequently contains foreign matter, such as bits of wood, metal shavings, small pieces of rubber or the like, and this 35 foreign matter clogs the apertures 21, thus preventing the proper discharge of the acid. When this occurs, the acid will rise in the tubular body portion 11 and force its way into the flange 14, and finally discharge into 40 the over-flow pipe 24. This over-flow pipe conducts the acid into the tower 5, without waste, but of course does not spray the same. When this over-flow operation occurs, it can be readily observed by the attendant as the 45 cover 25 is transparent. In order to restore the apparatus to its normal operation, the cover 25 is removed and the upper end of the over-flow pipe 24 engaged by a suitable instrument and elevated, whereby the valve 23 50 is unseated. This will effect the discharge of acid from the lower end of the tubular body portion 10, and this acid passing downwardly in proximity to the inner ends of the apertures 21, serve to clean or flush the same, 55 thereby removing from the apertures the foreign material, which has clogged the same. After this operation the over-flow pipe 24 may be returned to the normal position and the cover 25 placed over the flange 60 14. It is obvious that this operation may occur without cutting off the supply of acid to the chamber 13.

It is to be understood that the form of my invention herewith shown and described is 65 to be taken as a preferred example of the

same, and that various changes in the shape, size, and arrangement of parts may be resorted to without departing from the spirit of the invention or the scope of the subjoined claims.

Having thus described my invention, I claim:

1. In apparatus of the character described, a tubular body portion provided at its lower end with a main discharge opening 70 and a plurality of permanently open discharge apertures disposed above the main discharge opening, and a tubular over-flow pipe having both ends open and provided at its lower end with a valve adapted to cover and uncover the main discharge opening and incapable of closing the permanently open discharge apertures and having its upper end projecting into the upper portion of the tubular body portion.

2. In apparatus of the character described, a tubular body portion provided at its lower end with a main discharge opening and a plurality of permanently open discharge apertures disposed near the same, a valve to 90 cover and uncover the main discharge opening and incapable of closing the permanently open discharge apertures, and a longitudinally movable over-flow conduit extending longitudinally within the body portion and 95 having connection with the valve to move the same.

3. In apparatus of the character described, a tubular body portion provided at its lower end with a tapered extension having a main 100 discharge opening and permanently open discharge apertures disposed near the same, a valve to cover and uncover the main discharge opening and incapable of closing the permanently open discharge apertures, a 105 longitudinally movable over-flow conduit extending longitudinally within the body portion and having connection with the valve to move the same, and means to supply a liquid into the tubular body portion.

4. In apparatus of the character described, a tubular body portion provided at its lower end with a main discharge opening and a plurality of discharge apertures disposed 115 near the same, a valve to cover and uncover the main discharge opening, a longitudinally movable over-flow conduit extending longitudinally within the tubular body portion and having connection with the valve to move it, means to supply liquid into the 120 upper end of the tubular body portion, and a transparent cover for the upper end of the tubular body portion.

5. In apparatus of the character described, a chamber for receiving a liquid, a tubular body portion connected with the lower portion of the chamber, a flange disposed within the chamber near the upper end of the tubular body portion, a transparent cover disposed within the chamber and extending 125 130

downwardly between the flange and the side wall of the chamber, means for supporting the transparent cover in spaced relation to the bottom of the chamber, a tapered extension carried by the lower end of the tubular body portion and provided with a main discharge opening and discharge apertures disposed near the same, and a longitudinally movable over-flow conduit extending longitudinally of the tubular body portion and

provided at its lower end with a valve to cover and uncover the main discharge opening.

In testimony whereof I affix my signature in presence of two witnesses.

INGENUIN HECHENBLEIKNER.
